HARRY H. WATERMAN Inventor

Chas. K. Davies

Attorney

UNITED STATES PATENT OFFICE.

HARRY H. WATERMAN, OF STRASBURG JUNCTION, VIRGINIA.

PNEUMATIC SEPARATOR.

Application filed September 20, 1921. Serial No. 501,914.

To all whom it may concern:

Be it known that I, HARRY H. WATERMAN, a citizen of the United States, residing at Strasburg Junction, in the county of Shenandoah, State of Virginia, have invented a new and useful Pneumatic Separator, of which the following is a specification.

My present invention relates to improvements in pneumatic separators for use in connection with comminuted material for separating the finer particles thereof from the coarser or heavier materials therein, while the material is in suspension.

In the accompanying drawings I have illustrated one complete example of the physical embodiment of my invention, wherein the process and apparatus are utilized for the purpose of separating hydrated lime after it has been received from the pulverizer, but it will be readily understood that the process and apparatus are well adapted for use in the separation of lighter or finer materials from phosphate rock, roofing slag, grains, lime stone screenings and other comminuted material wherein it is desired to separate the dust or finer particles from the coarser material or tailings. Therefore, while I shall hereinafter refer to the invention as embodied in a lime separator, it will be evident that this is only one exemplification of the process and apparatus for carrying out the principles of my invention. And while I have illustrated a specific form of apparatus designed as a lime separator, it will also be understood that this is one example of the combination and arrangement of parts that I may use for the embodiment of my invention, and that changes and alterations may be made within the scope of my claims without departing from the spirit of the invention.

The invention consists essentially in the process and apparatus for agitating and suspending the comminuted material, and while the material is in suspension, subjecting it to the action of a pneumatic blast for separating and carrying off the lighter or finer particles, and means are provided whereby the material is fed at the discharge end of the receptacle for the finer particles. The source of the pneumatic blast is located at the tail end of the agitator thus

insuring a proportional increase in the strength of the pneumatic blast in its action on the material as the heavier particles are agitated and conveyed nearer to the source of the blast. The invention further consists in certain novel combinations and arrangements of parts as will be hereinafter more fully described and set forth in my claims.

In the accompanying drawings I have exemplified a lime separator, wherein:

Figure 1 is a view in side elevation of the complete embodiment of my invention.

Figure 2 is a top plan view of the apparatus of Fig. 1, showing some of the operating parts in dotted lines.

Figure 3 is a longitudinal, vertical sectional view through the separating drum and its hood, together with the charging hopper, and other features in connection therewith.

Figure 4 is a sectional view at line 4—4 in Fig. 3 through the hood and showing staggered, retaining plates in the intake end of the drum.

Figure 5 is an end view at line 5—5 of Figure 3 of the inclined, rotary drum or agitator.

Figure 6 is a detail sectional view of an air blast regulator or valve used in connection with the blast and exhaust pipes.

In the form of the invention exemplified in the drawings a base 1 of concrete or other suitable material is used for the supporting frame 2, and upon the latter the operating parts of the apparatus are supported. For separating, agitating, and holding the comminuted material in suspension I may use an inclined, rotary drum 3, which is preferably of metal, cylindrical in shape, open at both ends, and provided with the usual form of annular flanges or rings 4 on its exterior surface. Through the instrumentality of the pair of rings or annular flanges the drum is supported at the desired angle on pairs of flanged rollers or wheels 5, 5, which are also utilized for revolving or rotating the drum. The shafts 6 of these rollers extend longitudinally of the drum and beneath it and the shafts are revolved from the transversely disposed gear shaft 7 by means of the beveled gear

sets 8, 8, as seen in Fig. 2. The gear shaft is operated from the main drive shaft 9 located transversely of the drum and parallel with the gear shaft, and the sprocket 5 wheel 10 on shaft 9, sprocket chain 11 and sprocket wheel 12 on shaft 7 transmit power to the gear shaft for revolving the drum.

A main driving wheel or pulley is indicated at 13 on the shaft 9 and power may be 10 applied thereto from a suitable source (not shown) for actuating the several operating parts of the apparatus or plant.

The open end inclined drum is provided on its inferior periphery with longitudinally 15 extending ribs or cleats 14, preferably made up of angle irons and riveted or otherwise secured to the drum, for the purpose of elevating and dropping the material supplied thereto, and the heavier material or tailings 20 eventually pass out of the lower end of the drum, at the left in Figure 3. At the upper or intake end of the drum I utilize retaining plates 15 and 16, which are staggered and extend in annular series around the 25 inner surface of the drum adjacent its end. These plates may be integral portions of rings secured to the inner surface of the drum and the flanges of these rings may be notched, in order to provide the staggered 30 effect as seen in Fig. 4, to effectually prevent loss of material as it enters the drum, and yet permit passage from the drum of light or fine particles of the material or lime.

The discharge end of the drum for fine 35 lime is enclosed by a hood 17, which may be constructed of metal and is rigidly supported as in a frame 18, with a circular or annular flange 17' overlapping the discharge end of the drum with sufficient space for 40 rotation of the latter therein.

The hydrated lime as it is received from the hydrator or pulverizer in comminuted form is introduced to the rotary drum through the charging hopper 19, which is 45 rigidly supported in the top of the hood 17, passes therethrough and has its delivery spout 19' terminating just within the inner series of retaining plates 16 and near the bottom of the drum. The comminuted lime 50 is thus fed to the bottom of the revolving drum and as the latter rotates or revolves, the lime is picked up by the longitudinal cleats or ribs 14 and elevated, and as the material approaches the top portion of the 55 drum it is gradually dropped from the ribs, falling through the drum by gravity, and while in suspension is acted on as will be described.

At the bottom of the hood is located the 60 discharge spout 20 through which the separated and fine lime may be passed to the bin or other waiting receptacle, in usual manner. The separated lime is guided in its movement toward the discharge spout by 65 means of a transversely extending plate or

partition 21 within the hood and diverging from the open end of the drum. The guide plate or partition extends a sufficient distance toward the discharge spout to effectively guide and direct the fine materials 70 thereto, and terminates above said spout in order to provide an exhaust chamber 22 in the back of the hood which chamber is open at the bottom as indicated.

Within the exhaust chamber are arranged 75 two series of inclined baffle plates 23 and 24, which overlap, and are designed to arrest the finest particles of lime and cause them to fall into the discharge spout.

The comminuted lime after being fed to the drum is agitated by the lifting action of the longitudinal ribs as the drum revolves, and the suspended lime is subjected to the action of air blast injected through the drum from the tail end thereof toward the upper 85 end, which is both the inlet and outlet end for the lime. For the air blast I utilize an injector pipe 25 and injector nozzle 26, the latter centrally located, as indicated in dotted lines, in the open end of the drum 90 at the left in Fig. 3.

The air blast is supplied from the conventionalized fan blower 27, of the bottom horizontal discharge type, operated by the main shaft 9, and the blast passing through 95 the injector pipe is regulated by the blast regulator 28 in said pipe. The discharge from the nozzle will be apparent from the diverging dotted lines in Fig. 3, and it will be seen that the pressure from the nozzle 100 does not reach the walls of the drum, except at the outlet end for the fine lime. Thus the minimum pressure of the blast is applied at the point of maximum quantity of fine lime and this finely comminuted lime, while in 105 suspension, is blown toward the deflecting plate 21 in the hood and directed to the outlet or discharge spout 20, and thence transferred to the bin.

As the drum revolves the material or lime 110 fed thereto is continuously being agitated, elevated, and then dropped in suspension to fall to the bottom of the drum, and it will also be apparent that the heavier materials will travel by gravitation to the tail end of 115 the drum. Thus as the lime is fed to the drum the finest particles and dust are separated by the low pressure blast and passed to the discharge spout from the inlet end of the drum, while heavier particles 120 which may resist the low pressure are continually being agitated by the revolving drum and are gradually passing toward the tail end. As these heavier particles encounter the increasing pressure 125 of the blast the comminuted material which could not be separated by the low pressure is now separated due to the increased pressure of the blast, and when the coarser material that is too heavy to be blown by 130

the maximum pressure of the blast reaches the tail end of the drum, the last of the fine or light particles have been separated therefrom and blown to the discharge spout. In 5 this manner the lime is continually agitated and continuously subjected to increasing air pressure for thoroughly and effectively separating the light materials therefrom, until the tailings eventually fall out of the tail 10 end of the drum. These tailings may be returned to the pulverizer and again fed to the separator.

The separator is thus supplied with fresh and clean air at all times, drawn from the 15 atmosphere by the blower 27, and the blast or current of air passing through the injector pipe is governed or regulated by the blast regulator 28. A detail drawing of this device is illustrated in Fig. 6, wherein 20 a cylindrical valve member 29 is disposed transversely of the blast pipe, and provided with ports 30 in its walls. The valve member may be turned or revolved in its casing 25 by turning the handle 31 as shown in Fig. 2, thus opening or closing or partially closing the ports, to govern the passage of air currents therethrough.

When the fine particles of finished lime are separated in the drum and directed to 30 the hood, the baffle plates 23, 24 in the exhaust chamber 22 are designed to prevent escape of the finer particles with the spent air. However, any finished lime that may remain in suspension in the spent air is re- 35 covered from the exhaust chamber by means of an exhauster 32. The exhauster is also actuated by the main shaft 9, and is shown as a top horizontal discharge type of pneumatic fan. The exhauster 32 has a dust collecting pipe 33 attached thereto, and is pro- 40 vided with a vent pipe 34 in said collecting pipe. The strength of the suction or induced currents of air passing through the collecting pipe may be regulated by the 45 valve 35 located in the vent pipe 34, which valve is similar in construction to that illustrated in detail in Fig. 6.

The nozzle or inlet end of the collecting pipe for the spent air is indicated at 36, in- 50 side the exhaust chamber 22 of the hood, and it will be apparent that very fine material remaining in suspension may be drawn through the pipe 33, and then be blown through the conveyer pipe 37, which is also 55 provided with a regulator 38, to the collector indicated at 39. The collector 39 may be of any approved type, and is utilized for the purpose of recovering the last degree the 60 finished lime that may pass through the separator.

There are many advantageous features 65 accruing from the above described and illustrated invention including an effective and thorough stripping of the finished mate- rial from all of the tailings. This is ac-

complished by the continuous agitation im- 70 parted to the material, and the subjection of the material to a continuously increasing pressure of air as the lime is fed to the drum and the material passes toward the tail end 75 of the drum. The use of a direct blast of air through the drum or separating vessel requires the expenditure of less horse power than is usually applied to separators of this type. The desired fineness of the material 80 may be accomplished by the use of the blast regulating valves in the injector pipe, without the necessity for varying the speed of the blower, and the same adjustment may be accomplished in the exhaust or suction 85 device for collecting the lime dust.

The introduction of the air blast at one end of the agitator or separating vessel, and the introduction of the material to be sep- 90 arated at the opposite end of the vessel or receptacle prevents access of the maximum pressure of the blast to the bulk of the material as it is fed to the agitator and permits a wide distribution of the material within the receptacle in order that the required pressure may be applied to the material for the most effective results. In this manner the material is continuously being picked up and dropped across the air blast and the 95 particles that are not heavy enough to pass through the air currents are blown toward the discharge end of the vessel, thus sub- jecting the material to an increasing blast as the material nears the tail end of the agitator. The separation is assisted by drop- 100 ping the material on the metallic bottom of the agitator which tends to relieve the tailings of the finer material which latter is then subjected to the air blast and blown to the discharge.

Having thus fully described my invention, what I claim as new and desire to secure by Letters Patent is—

1. The combination with a fixed hood and a feed hopper therein, of an inclined rotary drum, a blower at the tail end of the drum and an outlet for finished material at the opposite end of the drum, a deflecting plate within the hood for finished material and forming an exit chamber for spent air, baffle 110 plates within said chamber for retarding exit of finished material, a dust collector, and an exhaust pipe connecting said collector and hood.

2. The combination with a rotary agitator having closed ends and an outlet for finished material, of a feed hopper at one end of the agitator and a blower at the other end of the agitator, a dust collector, and an ex- 115 haust pipe connecting said agitator and collector.

3. The combination with a rotary drum having a hood closing one end and an outlet for finished material, of a feed hopper in the hood, a blower at one end of the agi- 120 125 130

tator, a deflecting plate within the hood forming an exhaust chamber, a baffle plate within the chamber for retarding exit of finished material, a dust collector, and an 5 exhaust pipe connecting said collector and exhaust chamber.

4. In a separator the combination with a rotary agitating drum, of a hood and a head

closing the ends of the drum, a feed supply pipe to said head, a fan blower having its 10 intake end connected to said head, a discharge pipe for the blower, a dust collector on the discharge pipe, and an air supply pipe to said hood.

HARRY H. WATERMAN.
